UNITED STATES PATENT OFFICE

IRA O. BANKS, OF HIGGINSVILLE, MISSOURI, ASSIGNOR OF ONE-HALF TO PAUL R. HEIDBRINK, OF HIGGINSVILLE, MISSOURI

RADIO ANTENNA

Application filed May 1, 1931. Serial No. 534,422.

This invention relates to radio antenna and it is an object of the invention to provide a device for controlling the length of the antenna to vary the effective tone and volume of a radio receiving set and to vary the capacity of the outside ground.

Another object of the invention is to provide a device adapted for use with sets operating on alternating or direct current circuits with the wiring or circuit of the device serving as an indoor antenna for the radio receiver. The device serves as a control for varying the signals to the antenna and to vary the potential drop between the ground of the set and the antenna post of the set, thus effectively varying the volume of the signal received.

Referring to the accompanying drawing, which is made a part hereof and on which similar reference characters indicate similar parts,

Figure 1 is a plan view of the device,

Figure 2, an underside view opposite to that shown in Figure 1, and

Figure 3, a diagrammatic view of the device.

In the drawing numeral 10 indicates the casing in which the parts are enclosed. Mounted upon the casing are posts 11, 12 and 13 to which suitable wires 25, 26 and 27 are connected to the radio set antenna post A, to the ground post of the radio set G and to the outside ground Gr respectively. Post 13 is connected by means of a wire 14 to post 15 which is in turn connected to an arm 16 having a roller 17 adapted to engage a resistance 18 built in the form of a coil, the ends of the resistance 18 terminating at posts 19 and 20 respectively. A wire 21 connects post 20 to post 12. Post 19 is connected by a wire 22 to one side of a condenser 23, the other side of the condenser being connected to post 11 by wire 24.

A shaft 28 on which arm 16 is mounted is provided with a knob 29 on the face of the casing 10 for operating the device.

Numeral 30 indicates an outside antenna and lead-in wire connected to the antenna post A of the radio set and for use if an outside antenna is desired to be used with this

device. In most cases better results are obtained when the device and an outdoor antenna are available.

The operation of the device is as follows: By setting the knob 29 so that the arm 16 carrying the roller 17 is in contact with post 20 a direct connection from the outside ground to the ground of the set is completed which substantially reduces the signals coming in on the circuit of the device when it is used as an indoor antenna. By connecting the outside antenna 30 to post A to which lead 25 from post 11 of the device is also attached, signals will come in on the outside antenna since all the resistance 18 lies between the ground and antenna posts of the set.

By turning the knob 29 clockwise the roller 17 can be made to divide the resistance 18 into two equal portions. This gives a balancing effect and signals are now coming in on the outside antenna and the device which serves as an inside antenna. Signals are now obtained from both indoor and outside antennae. Continuing in the same direction (clockwise) a stronger ground is obtained and hence stronger radio signals, which signals continue to increase as the knob 29 is rotated to a point where the roller 17 contacts with post 19. At this limit the incoming signals are now obtained through the indoor antenna (the device) and controlled by this device.

At all times the condenser 23 is in line 24 in both cases whether signals are coming in on the device which serves as an indoor antenna or on the outside antenna. The resistance may vary between the post 18 with respect to posts 11 and 12; it is always the same between posts 11 and 12. No connection is made between post 11 and post 12 since the antenna leads are connected to the condenser 23.

By use of this device it is possible to vary the volume and control by rotation of the knob from one extreme to the other and either antenna may be used, or both, and controlled by this device which itself serves as the indoor antenna, thereby providing a wide range of control for the radio receiving set and with such a range it is possible to obtain the

most satisfactory results regardless of atmospheric conditions.

It will be obvious to those skilled in the art that various changes may be made in my device without departing from the spirit of the invention and therefore I do not limit myself to what is shown in the drawing and described in the specification, but only as indicated by the appended claim.

10 Having thus fully described my said invention, what I claim as new and desire to secure by Letters Patent, is:

15 A variable antenna control for a radio receiver having an antenna post and a ground post comprising a resistance and a condenser connected in series between the antenna post and the ground post of the radio receiver and a grounded arm rotatably mounted in contact with said resistance adapted to vary the potential drop between said antenna and ground posts of the radio receiver, substantially as set forth.

20 In witness whereof, I have hereunto set my hand at Higginsville, Missouri, this 27th day of April, A. D., nineteen hundred and thirty-one.

IRA O. BANKS.
